(57) **CLAIM**

The ornamental design for a drinking fountain, as shown and described.

DESCRIPTION

FIG. 1 is a perspective view, taken from the front, top, and right side, of a drinking fountain, in accordance with our new design.

FIG. 2 is a perspective view, taken from the top, front, and left side of the drinking fountain shown in FIG. 1.

FIG. 3 is a top plan view of the drinking fountain shown in FIG. 1.

FIG. 4 is a bottom plan view of the drinking fountain shown in FIG. 1.

FIG. 5 is a right side elevation view of the drinking fountain shown in FIG. 1.

FIG. 6 is a left side elevation view of the drinking fountain shown in FIG. 1.

FIG. 7 is a front elevation view of the drinking fountain shown in FIG. 1; and,

FIG. 8 is a rear elevation view of the drinking fountain shown in FIG. 1.

The broken lines illustrate environmental structure which forms no part of the claimed design. The article is shown with a symbolic break in its height. The appearance of any features of the article between the break lines forms no part of the claimed design.

1 Claim, 7 Drawing Sheets
